EDGAR S. NETHERCUT, OF EVANSTON, ILLINOIS.

RAILWAY-RAIL STRUCTURE.

940,818.

Specification of Letters Patent. Patented Nov. 23, 1909.

Application filed April 5, 1909. Serial No. 488,690.

To all whom it may concern:

Be it known that I, EDGAR S. NETHERCUT, a citizen of the United States, residing at Evanston, in the county of Cook and State of Illinois, have invented certain new and useful Improvements in Railway-Rail Structures, of which the following is a specification.

This invention relates to the construction 10 of rail structures wherein one rail crosses or diverges from another rail, such as right-angle and acute-angle crossings, frogs, mates, and run-offs.

The invention will be herein described as 15 applied to a crossing.

In the construction of crossings it is now good practice to make the top of the rail or running surface in one plane, and to raise the bed of the throatway by means of an incline from the normal position at some distance from the intersection of the throatways to a height which is below the normal top of the rail by an amount equal to the depth of the flange of the car wheel. With 20 such an arrangement of the throatway the wheel flange carries the wheel across the other throatway in a level plane. If the bottom of the throatway were not thus raised with relation to the top of the rail the wheel 25 would have no support in passing over the other throatway. This would be of only an instant's duration but sufficient to cause a slight drop with its attendant pound on the top of the rail. The result would soon be a 30 pounding down of the crossing surface at this point and a tendency to break up the crossing structure.

Because of the double service upon the head of the crossing structure which carries 35 the treads of the wheels at the intersection of the throatways, this portion of the crossing wears faster than the parts of the top of the crossing away from the intersection of the throatways, the beds of the throatways 40 likewise being worn down. It is customary to prevent undue pounding of the wheel at this point by grinding the top of the crossing structure at the intersection of the rails to a new surface, and forming a gradual decline from the normal top of the rail to the 45 new surface. In this manner and at small expense the structure is maintained without the otherwise attendant pound and noise. This maintenance can be continued until the 50 incline becomes so abrupt as to become a

drop, at which time the usual life of the structure is at an end.

My invention consists in adding metal to the normal top of the crossing structure at the point of maximum wear and providing a 60 suitable incline so that this elevated surface may be reached without jar. By so doing, additional life is gained, and the use of high-priced metal in other parts than those receiving the wear is made economical. 65

In the accompanying drawings, Figure 1 is a top plan view of a right-angle crossing structure embodying the features of my invention. Fig. 2 is a top plan view of a portion of said crossing. Figs. 3 and 4 are sections on lines 3 3 and 4 4, respectively, of Fig. 2.

Referring to Fig. 3, it will be seen that the portion 1 of the heads of the crossing rails at the intersection of said rails is 75 thicker than the outer ends of said rails as to raise the tread portion 2 above the normal plane of the rails, inclined portions 3 being provided so that the surface 2 may be reached without jar. The bottoms of the 80 grooves or throatways 4 are raised, by means of inclines 5, from their normal position, so that at the intersection of said throatways the bottoms thereof are below the surfaces 2 a distance equal to the depth of the flange 85 of the car wheel. When the structure is in good condition, the flange of the wheel, running upon the bed of the throatway, carries the wheel over the intersection of the throatways without shock. When the tread 90 portion 2 and the bed of the throatways have worn down so as to form depressions which cause an undue amount of pounding, the head 1 and the beds of the throatways are ground down sufficiently to remove 95 the depressions. In the course of time, repeated wear and grinding brings the tread surface 2 into the normal plane of the rails, after which continued wear and grinding finally reduces the running surface and the 100 throatway to the position indicated by dotted lines in Fig. 3.

It will be seen that my invention doubles the life of the structure, since there is twice as much metal in the structure to be removed by wear and maintenance work. 105

I have herein shown the invention as applied to a crossing assumed to be made wholly of hard and tough metal, as, for example, manganese steel, but it will be un- 110

derstood that the invention may be embodied in structures wherein only the portions receiving the maximum wear are formed of such material.

5 My invention, by lengthening the life of the structure, makes economical the use of such high-priced metal as manganese steel in other parts than those subjected to the greatest wear.

10 It will be understood that the invention is applicable not only to crossings of various forms, but to frogs, mates, and other structures wherein one rail crosses or diverges from another.

15 I claim as my invention:

1. A railway rail structure comprising two rails which meet each other, the heads of the rails at the meeting point being thickened to elevate the tread surface at said point above the normal plane of the tread surface, and inclines connecting the ele-

vated tread portion with the tread portions of normal height.

2. A railway rail structure comprising two rails which meet each other, the heads 25 of the rails at the meeting point being thickened to elevate the tread surface at said point above the normal plane of the tread surface, and inclines connecting the elevated tread portion with the tread portions of 30 normal height, each of said rails having a throatway therein, and the beds of said throatways being inclined upwardly toward the meeting point to a point below the elevated tread surface at the meeting point, the 35 depth of said throatways at the meeting point being not greater than the depth of a car wheel flange.

EDGAR S. NETHERCUT.
